UNITED STATES PATENT OFFICE

ROBERT PATON, OF CARDONALD, NEAR GLASGOW, SCOTLAND, ASSIGNOR TO THE BAR-
COCK & WILCOX COMPANY, OF BAYONNE, NEW JERSEY, A CORPORATION OF NEW
JERSEY

SUPERHEATER FOR STEAM GENERATORS

Application filed October 1, 1925, Serial No. 59,784, and in Great Britain December 18, 1924.

This invention relates to steam superheaters in which a large decrease of pressure of the steam passing through the superheater is avoided, and the invention will be understood from the description in connection with the accompanying drawings, in which Fig. 1 is a vertical section through a steam boiler in connection with which an illustrated embodiment of the invention is shown; Fig. 2 is a front view of the same partly broken away; Fig. 3 is a view similar to Fig. 1 showing a modification; and Fig. 4 is a front view similar to Fig. 2.

In the drawings, reference character 10 indicates a bank of tubes of a water-tube boiler which terminates in headers 11 and 12 and are installed above a furnace of a boiler so as to be contacted by the hot gases or products of combustion from the furnace. The steam and water drum 13 of a usual type is connected by means of tubes 14 and 15 to the headers 11 and 12, the tubes 14 being interposed in the path of the hot gases, as indicated.

As illustrated in the accompanying drawings, the improved superheater is installed in the gas passage that is provided above the tubes 14, but it will be understood that this is for illustrative purposes, as the superheater itself may be installed in other locations.

Saturated steam pipes 16 and 16' lead from the steam space near the respective ends of the drum 13 to upper headers 17 and 17' of the superheater which are divided into sections by partitions 18 and 18', which sections will be termed entry and exit sections, respectively. Lower superheater headers 19 and 19' are connected by sets of tubes 20 and 20' to the entry sections of headers 17 and 17' and by sets of tubes 20₁ and 20'₁ to the exit sections of headers 17 and 17'. The tubes connecting the headers 17 and 19 may be provided with one or more reverse bends and these tubes constitute the tubes of the superheater, being located in the superheater space of the boiler so that hot gases will contact therewith. Nipples 21 and 21' connect the exit sections of headers 17 and 17' to a common header 22 and tubes 23 connect this common header 22 to another header 24 from

which the superheated steam pipe 25 leads to an engine or other place where the steam is to be used.

The saturated steam from the steam space of the drum 13 passes, as shown by the arrows 55 on the drawings, through pipes 16 and 16' to the entry sections of the headers 17 and 17', thence through the tubes 20 and 20' to the headers 19 and 19', through the tubes 20₁ and 20'₁ to the exit sections of headers 17 and 17', through the nipples 21 and 21' to the header 22, through the tubes 23 to the header 24 and thence into the pipe 25, the steam being superheated as it passes through the tubes 20, 20', 20₁ and 20'₁. It is thus seen that the steam enters the superheater headers at a plurality of points and travels in multiple paths through the heating space thereby securing an even distribution of the steam between the superheater tubes with a lower frictional resistance to the flow of steam through the superheater than would be obtainable with the steam entering the superheater at a single point.

In the modification shown in Figs. 3 and 4, the saturated steam pipes 36 and 36' lead from the steam space near the respective ends of the drum 13 to the entry sections of the upper headers 37 and 37' of the superheater which are divided into entry and exit sections, as above described in connection with headers 17 and 17'. The entry sections of headers 37 and 37' are connected by nipples 41 and 41' to the entry sections of headers 39 and 39', which headers are likewise divided into entry and exit sections by means of partitions 40 and 40'.

Sets of superheater tubes 42 and 42' which may be provided with one or more reverse bends, lead from the entry sections of headers 39 and 39' to the lower headers 43 and 43' of the superheater. Similar sets of superheater tubes 42₁ and 42'₁ in the same plane, lead from the headers 43 and 43' to the exit sections of headers 39 and 39'. Sets of tubes 44 and 44' lead from the entry sections of headers 37 and 37' to headers 45 and 45' which are shorter than the headers 43 and 43'. Sets of superheater tubes 44₁ and 44'₁ similar to sets 44 and 44' lead from the head-

ers 45 and 45' in the same plane to the exit sections of headers 37 and 37'. Nipples 46 connect the exit sections of the headers 37 and 39, and nipples 46' connect the exit sections of headers 37' and 39'. Tubes 48 lead from the exit sections of headers 37 and 37' to a header 49 from which a saturated steam pipe 50 leads to a steam engine or other place where the steam is to be used.

- 10 In operation, saturated steam passes through the pipes 36 and 36' from the drum 13 to the entry sections of the headers 37 and 37' where the steam divides, part of it passing through the nipples 41 and 41' to the entry sections of the headers 39 and 39'. The steam then passes from the entry sections of the respective headers 37, 37', 39 and 39' in "parallel" through the superheater tubes 42, 42', 44 and 44' to the headers 43, 43', 45 and 45', thence through the superheater tubes 42₁, 42'₁, 44₁ and 44'₁ to the exit sections of the headers 37, 37', 39 and 39'. The steam entering the exit sections of the headers 39 and 39' passes through the nipples 46 and 46' into the exit sections of the headers 37 and 37' uniting with other superheated steam therein, and all of the superheated steam passes through tubes 48 and thence through pipe 50 to the engine or the like.
- 15 20 25 30 Changes may be made in the details of construction and in the arrangement of the parts above described without departing from the spirit of my invention.

I claim:

- 35 1. In a steam superheater, horizontally disposed upper headers and lower headers connected by tubes, a plurality of saturated steam inlets to said upper headers, and means for withdrawing superheated steam from said upper headers.
- 40 2. In a steam superheater, horizontally disposed upper headers and lower headers connected by tubes, a plurality of saturated steam inlets to said upper headers, and a common outlet for said upper headers.
- 45 3. In a steam superheater, horizontally disposed upper headers and lower headers connected by tubes, said upper headers being divided into sections, a plurality of saturated steam inlets to said upper headers, and means for withdrawing superheated steam from said upper headers.
- 50 4. In a steam superheater, horizontally disposed upper headers and lower headers connected by tubes, a plurality of saturated steam inlets to said upper headers, and means for causing steam to travel in opposite directions in different ones of said tubes.
- 55 60 65 65 5. In a steam superheater, horizontally disposed upper headers and lower headers connected by tubes, a plurality of saturated steam inlets to said upper headers, and means for causing steam to travel in one direction through tubes near one end of said

headers and in the opposite direction through tubes near the other ends thereof.

6. In a steam superheater, horizontally disposed upper headers and lower headers connected by tubes, a plurality of saturated steam inlets to said upper headers, and means for causing steam to pass through said tubes from said upper headers to said lower headers and back again.

7. In a steam superheater, horizontally disposed upper headers and lower headers connected by tubes, a plurality of saturated steam inlets to said upper headers, said upper headers being divided into sections and means for conducting steam from one section to a lower header and thence to another section of said upper header.

8. In a steam superheater, horizontally disposed upper headers and lower headers connected by tubes, a plurality of saturated steam inlets to said upper headers, and means to pass steam between said headers in a plurality of paths in parallel.

9. In a superheater, a plurality of aligned steam inlet headers each divided into sections, groups of superheater tubes each group being connected in parallel respectively to a section of said headers, headers to which said groups of tubes are connected, and a group of tubes from each of said last named headers each group leading to another section of said aligned headers and an outlet header connected to all of said last named sections.

10. In a superheater for a steam boiler having a steam and water drum, inlet headers substantially parallel to said drum, a plurality of saturated steam inlets from said drum to said headers, and a superheated steam outlet from said superheater at substantially the same level as said inlet headers.

11. In a superheater for a steam boiler having a steam and water drum, inlet headers substantially parallel to said drum, a plurality of saturated steam inlets from said drum to said headers, a row of reverse bend tubes connected to said headers located in a single gas path, and a superheated steam outlet from said superheater at substantially the same level as said inlet headers.

12. In a superheater for a steam boiler having a steam and water drum, said superheater comprising headers and tubes and formed in a plurality of sections subjected to the same heating gases, and means to conduct steam separately from the drum to the tubes in each of said sections.

ROBERT PATON.
